UNITED STATES PATENT OFFICE

2,658,611

WIRE DRAWING BLOCK AND STRIPPER
ASSEMBLY

Edwin J. McIlvried, Stow, Ohio, assignor to The
Vaughn Machinery Company, Cuyahoga Falls,
Ohio, a corporation of Ohio

Application November 21, 1950, Serial No. 196,806

6 Claims. (Cl. 205—20)

1

This invention relates as indicated to a wire drawing block and stripper assembly, and more particularly to a wire drawing block and riding stripper adapted for the accumulation of an unusually large bundle of wire before it becomes necessary to remove the same.

As wire is drawn through a die and wound upon a take-up block, it is, of course, subjected to very considerable tension and is wound very tightly about the block or drum making it difficult for the lowermost turn of wire to force the preceding turns upwardly. The block is conventionally provided with a radius in its lower wire-engaging portion so that the component of thrust of the lowermost turn of wire is not directly upwardly but, rather, at an angle. When, because of friction and the accumulated weight of previous turns of wire making up the coil or bundle, the lowermost turn is no longer able to force such preceding turns upwardly, it will override the next preceding turn, whereupon the drawing operation must then be interrupted and the accumulated bundle of wire removed. The more frequently this occurs, the less efficient the drawing operation, since not only is down time increased and the attention of a skilled operator required, but also most difficulties encountered in wire drawing operations develop when starting the machines. It is highly desirable that a drawing operation when once commenced should continue as long as possible.

It is accordingly a primary object of my invention to provide a wire drawing block and stripper assembly capable of accumulating a very large bundle of wire thereon before it becomes necessary to interrupt the drawing operation for removal of the bundle.

Another object is to provide a wire drawing block and riding stripper assembly capable of accumulating a very large bundle or coil of untangled wire before overriding of the wire on the block necessitates removal of such bundle.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a vertical sectional view through my

2

new wire drawing block and stripper assembly taken on the line 1—1 on Fig. 2;

Fig. 2 is a top plan view of such block;

Fig. 3 is a vertical sectional view diametrically of the block and stripper assembly;

Fig. 4 is an enlarged fragmentary detail view of a modification of the block construction;

Fig. 5 is a fragmentary elevational view of the upper portion of the stripper device; and

Fig. 6 is a sectional detail view taken on the line 6—6 on Fig. 3.

Referring now more particularly to said drawing, the embodiment of my invention there illustrated comprises the usual housing 1 seated in

15 an opening 2 in bench 3 and including a gear box 4 in which the lower end of spindle 5 is journaled in appropriate thrust bearing 6. The usual filler plug 7 and drain plug 8 are provided for such gear box. Spindle 5 is also journaled in an upper bearing 9 within upper extension 10 of such gear box and is driven in the usual manner by worm gear 11 keyed thereon in driven engagement with worm 12 on shaft 13 driven by electric motor 14.

25 Apron 15 is carried by spaced bearings 16 and 17 on upper extension 10, such latter bearings having an axis slightly inclined to the axis of spindle 5 so that any point on the surface of apron 15 will be caused to rock up and down once for each revolution. While the amount of relative inclination desired will depend on the diameter of the wire to be handled, in a typical installation such inclination may amount to approximately 1° to 5°. A generally annular 30 detachable hardened steel insert 18 will preferably be mounted in the inner periphery of such apron to provide a wear-resistant wire engaging surface adjacent the outer surface of the drum 19.

The drum 19 comprises a generally cylindrical 35 shell including a hub portion 20 keyed to spindle 5. Four equally spaced vertically extending radial slots 21, 22, 23 and 24 are provided in such drum to receive the respective feet of the riding stripper, as explained below. Corresponding extensions of such slots 25, 26, 27 and 28 are provided in apron 15.

40 Means are also provided interconnecting drum 19 and apron 15 for driving of the latter by the former comprising an inner boss 29 on drum 19 45 having a vertically extending opening 30 therethrough. A wobble pin 31 is bolted in apron 15 having an upper ovoid end portion 32 received within wear-resistant sleeve 33 in opening 30 of boss 29. Consequently, as drum 19 rotates, apron 55 15 is caused to turn therewith, but provision is

made for the relative rocking action of such apron resulting from the aforementioned misalignment of the axes of rotation of such drum and apron.

In Fig. 4 there is illustrated a modification of the above-described connecting means wherein a coil spring is employed instead of wobble pin 31. Spring 34 is secured within generally vertically extending sleeve or cylinder 35 mounted within drum or block 19, the lower end of such spring extending downwardly beyond the lower end of sleeve 35 and being received in cup 36 in apron 15. Such spring is relatively heavy and being enclosed except for the relatively short extent intermediate sleeve 35 and cup 36 affords a sufficiently rigid driving connection between the drum and apron. On the other hand, it is, of course, sufficiently flexible to accommodate the variation in angle between such sleeve and cup as the drum rotates as well as accommodating the necessary axial compression and extension resulting from the relative rocking action.

Spindle 5 has an upper extension 37 terminating in a tapered end adapted to receive and guide the tubular center member 38 of the riding stripper. The clevis 39 is provided at the upper end of tubular center member 38 to permit the stripper to be lifted from the block with its bundle of accumulated wire when desired. Four feet such as 40 and 41 are pivotally mounted at 42 and 43 on adjustable studs carried by collar 44 fixed to the lower end of tubular member 38. An upper collar 45 is mounted for reciprocation along tubular member 38 and is connected with the stripper feet by means of links such as 46 and 47. Obviously, when collar 45 is shifted upwardly, it will tend to rock the stripper feet outwardly and, conversely, when such collar 45 moves downwardly along member 38, the stripper feet will be rocked inwardly. A collar 48 or bosses such as 49 are welded to member 38 to limit such downward movement of collar 45. As best shown in Fig. 5, a yoke 50 is pivotally mounted on collar 45 and provided with a handle 51 for manipulation of the same. When the riding stripper is mounted on the block as shown in Figs. 1 and 3, the stripper feet received in slots 21, 22, 23 and 24 of the block and corresponding extension slots in the apron will have been cammed outwardly as shown, and collar 45 elevated above stop 48 or 49. Yoke 50 may then be swung inwardly into Fig. 5 position so that downward sliding movement of collar 45 will be prevented when the stripper is lifted from the block by clevis 39. The stripper feet will consequently be caused to remain in extended position so as to carry the accumulated bundle of wire.

As shown in Fig. 3, the extension 37 of spindle 5 and the stripper itself which is adapted to be mounted thereon are unusually high to accommodate a correspondingly high coil or bundle of wire W. In fact, the stripper may desirably extend above the block three times the vertical extent of the wire engaging surface of such block or even more. The stripper need not necessarily be of the collapsible type as illustrated and described but may instead be rigid. The block and stripper should, however, be designed so that such stripper may "ride" the block during the drawing operation and the accumulation of wire thereon since the accumulated bundle may then be lifted from the block without the tangling which ordinarily occurs when a stripper is inserted within an already accumulated bundle.

As the drum or block 19 rotates, the wire W is, of course, wound thereon while engaging hardened insert 18 in apron 15. As the block continues to turn, such apron is canted (Fig. 3), ordinarily on the order of from about 1-5° pushing such lowermost turn of wire upwardly on the block. Such lowermost turn, of course, likewise pushes the preceding turns before it. This positive push-up action is effective even after a very large number of turns have been accumulated on the drum or block and riding stripper, so that the drawing operation may be continued long past the point when overriding of the lowermost turn of wire would otherwise have occurred. It has been found possible, for example, by employment of apparatus in accordance with my invention, to accumulate on the order of 600 pounds of .033 inch diameter wire before it becomes necessary to interrupt the drawing operation, whereas previously from 60 to 80 pounds of such wire were all that could be accumulated before overriding and tangling would occur.

When the accumulated bundle has been lifted from the drum or block, the stripper may be transported to another station and mounted on an appropriate spindle so that the wire may be unwound therefrom as may be required for the next operation to be performed thereon. In view of the fact that it is thus possible to obtain a bundle comprising an exceptionally long length of wire in untangled condition, the necessity of first rewinding such wire on a spool or reel before utilizing the same in such subsequent operation is avoided. In addition to round wire, it will, of course, be appreciated that other similar articles such as flat wire, the smaller sizes of tubing, etc., are adapted to be handled by my new drum or block and riding stripper assembly. The combination of the push-up feature with the oversize riding stripper clearly makes possible the obtaining of very considerable economies in all such drawing operations.

As illustrated in the drawing, since the drum or block itself is not provided with the usual radius in its lower wire-engaging portion, the force exerted against the lowermost turn of wire, and thereby against the preceding turns, is substantially directly upwardly, whereby an arrangement is achieved effective to push up a much greater weight of wire. Relative sliding action between adjacent turns of wire, which in the past has tended to scratch the same, is also thereby avoided.

Other modes of applying the principle of the invention may be employed, change being made as regards the details described, provided the features stated in any of the following claims or the equivalent of such be employed.

I therefore particularly point out and distinctly claim as my invention:

1. In wire drawing mechanism including a rotatable wire drawing block, the combination of an annular apron closely encircling said block and mounted for rotation about an axis at a slight angle to said block, means flexibly interconnecting said block and apron for rotation of said apron with said block whereby said apron is caused to rock slightly relative to said block, drive means for said block, a wear-resistant insert secured to said apron adjacent the outer periphery of said block adapted to engage the lowermost turn of wire wound on said block and to push the same upwardly as said apron rocks, aligned radial grooves in said block and apron

adapted to receive the feet of a wire stripper, a wire stripper comprising a frame having feet received in such grooves, said stripper resting on said block for rotation therewith and extending upwardly above said block a distance approximately three times the vertical extent of the wire-engaging surface of said block, and cooperating positioning means on said block and stripper extending axially of said block.

2. In wire drawing mechanism including a rotatable wire drawing block, the combination of an annular apron closely encircling said block and mounted for rotation about an axis at a slight angle to said block, means flexibly interconnecting said block and apron for rotation of said apron with said block whereby said apron is caused to rock slightly relative to said block, drive means for said block, a riding stripper mounted on said block for rotation therewith, and an upwardly extending axial shaft on said block, said stripper having an axial tubular portion adapted to cooperate therewith for positioning of the same on said block and to facilitate mounting of said stripper after removal from said block with an accumulated coil of wire whereupon such wire may be unwound from said stripper and conducted directly to further processing mechanism.

3. In wire drawing mechanism including a rotatable wire drawing block, the combination of an annular apron closely encircling said block and mounted for rotation about an axis at a slight angle to said block, means flexibly interconnecting said block and apron for rotation of said apron with said block whereby said apron is caused to rock slightly relative to said block to push up the lowermost turn of wire thereon and thereby also the previous turns, drive means for said block and a riding stripper removably mounted on said block for rotation therewith and extending upwardly well above said block to receive a large accumulation of turns of wire thus pushed upwardly by said rocking apron.

4. In wire drawing mechanism including a rotatable wire drawing block, the combination

of an annular apron closely encircling said block and mounted for rotation about an axis at a slight angle to said block, means flexibly interconnecting said block and apron for rotation of said apron with said block comprising a coil spring secured within said block and having an axis generally parallel to but eccentric of the axis of said block whereby said apron is caused to rock slightly relative to said block to push up the lowermost turn of wire thereon and thereby also the previous turns, drive means for said block and a riding stripper removably mounted on said block for rotation therewith and extending upwardly well above said block to receive a large accumulation of turns of wire thus pushed upwardly by said rocking apron.

5. In wire drawing mechanism including a rotatable wire drawing block, the combination of an annular apron closely encircling said block and mounted for rotation about an axis at a slight angle to said block, means flexibly interconnecting said block and apron for rotation of said apron with said block comprising a tubular receptacle mounted within said block, an opposed tubular receptacle mounted in said apron, both said receptacles being generally parallel to the axis of said block, and a coil spring fitted within said receptacles and extending therebetween.

6. In wire drawing mechanism including a rotatable wire drawing block, the combination of an annular apron closely encircling said block and mounted for rotation about an axis at a slight angle to said block, and resiliently flexible means interconnecting said block and apron for rotation of said apron with said block.

EDWIN J. McILVRIED.
